United States Patent Office

Des. 229,090
Patented Nov. 6, 1973

229,090

LUMINAIRE

Eldon L. Anderson, Jr., Fletcher, N.C., assignor to
General Electric Company

Original design application June 1, 1970, Ser. No. 23,218,
now Patent No. 222,103. Divided and this application
Apr. 13, 1971, Ser. No. 133,777

Term of patent 14 years

Int. Cl. D26—05
U.S. Cl. D48—23 R

FIG. 1

FIG. 2

FIG. 3

FIG. 1 is a top plan view of a luminaire showing my new design;

FIG. 2 is a side elevational view thereof;

FIG. 3 is a bottom plan view thereof;

FIG. 4 is a top plan view of a luminaire embodying my new design;

FIG. 5 is an elevational view of the FIG. 4 luminaire; and

FIG. 6 is a bottom plan view thereof.

This is a division of design application Ser. No. D. 23,218, filed June 1, 1970 and now design patent Ser. No. D. 222,103.

I claim:

The ornamental design for a luminaire, as shown.
